UNITED STATES PATENT OFFICE.

WILLIAM F. KESSLER, OF AUBURN, INDIANA.

ELECTRIC CIGAR-LIGHTER.

SPECIFICATION forming part of Letters Patent No. 623,480, dated April 18, 1899.

Application filed October 17, 1898. Serial No. 693,704. (No model.)

To all whom it may concern:

Be it known that I, WILLIAM F. KESSLER, a citizen of the United States, residing at Auburn, in the county of De Kalb, in the State 5 of Indiana, have invented certain new and useful Improvements in Electric Cigar-Lighters; and I do hereby declare that the following is a full, clear, and exact description of the invention, which will enable others skilled 10 in the art to which it appertains to make and use the same, reference being had to the accompanying drawings, which form part of this specification.

My invention relates to improvements in 15 electric cigar-lighters.

The object of my present invention is to provide an automatic cigar-lighter of increased simplicity of construction and operation whose parts are so united that all portions 20 thereof are out of the path of the blaze when ignited for use, having a horizontal swiveled shell-body for the operative mechanism of novel arrangement, within which the spark is thrown; having a hand-lever in 25 close proximity to the bowl-handle, provided upon one end thereof with an extinguishing-cap and adapted to operate the sparking device by a positive movement; provided with improved means for establishing electrical 30 connection with the contact-point of the sparking-lever, and provided with a detachable connection with the supporting-arm.

The principal novel features of my invention are the construction and relative arrangement 35 of the containing-shell body and the manner and means for throwing the ignition-spark.

My invention consists of a horizontal shell-body rigidly fixed upon the vertical wick-tube and suspended from or in the supporting-frame by a pivotal connection and a hand-lever pivotally mounted adjacent to the wick-tube and carrying the extinguishing-cap and the sparking device.

In the accompanying drawings similar reference-numerals indicate like parts in the several views, in which—

Figure 1 is a side view of my improvement with a portion of the shell-casing broken away to show the operating hand-lever, extinguishing-cap, and sparking device in the relative positions they assume when the wick

is ignited. Fig. 2 is a similar view of the same, showing the shell-body, detachable cap 55 sparking-lever, and supporting-frame all in vertical section. Fig. 3 is a view in elevation of my improvement, taken at right angles to Figs. 1 and 2, showing, approximately, the relative position assumed by the shell-body when the wick is ignited for use. Fig. 4 is an enlarged detail of the means for detaching the lighter from its support. Fig. 5 is an enlarged plan of the shell-body, taken in transverse section, showing the contained mechanism. Fig. 6 is a detail view of the sparking device. 65

The metallic shell-body 6 in horizontal arrangement of any desired dimensions or contour, preferably rectangular, as shown, has a central circular blaze-opening upon its upper face and midway its ends, surrounded by 70 an upright annular flange 8. The oil-receptacle 1 has a proper lateral opening 48 for filling the same. At directly opposite points in the ends of said shell 6 and midway the sides thereof are arranged circular openings in 75 which are loosely mounted the inner ends of the tubular pivots 20, having an annular flange 21 and having their outer ends screw-threaded and adapted to fit corresponding screw-threaded openings in the adjacent end of the 80 supporting-frame, whereby the said shell-body has a swiveled connection with said supporting-frame, hereinafter described.

The shell or casing 6 has a longitudinal slot of proper dimensions in its lower face, extending somewhat past a point midway of its ends. In the inner end of this slot is arranged the upper end of the wick-tube 25, whose free end is oblique and preferably rectangular in cross-section, forming the burner, 85 which has its upper edge provided with a fixed steel wire 40 to prevent undue wear upon the contact-point of said tube or burner by the sparking device. To the lower end of this wick-tube is secured or cast integral therewith 90 a pear-shaped or cylindrical oil-receptacle or fluid-reservoir 1, which may be of any desired contour and is adapted to form a proper handle for my improvement. This receptacle 1 and the integral wick-tube 25 are rigidly secured to the said shell 6 by means of proper holding-screws 41, which pass through the bottom of said shell adjacent to said slot and are secured in the lug 7 on said tube, access 100

to said screws by a proper tool being afforded by the said circular opening in the upper face of the said shell. At a proper point on the side of said reservoir is arranged a lateral bifurcated lug 43, in which is pivotally fulcrumed an upright hand-lever 4, having a handle 5 upon its lower end adapted to be pressed against the said reservoir 1 by the hand of the operator, Fig. 1. The upper end 5 of said lever 4 is provided upon its inner face with a chambered lug having an oblique face adapted to snugly fit the said oblique face of the burner or wick-tube, thus forming an extinguishing-cap which is adapted to receive the slightly-protruding wick 42 without contact therewith, adapted to contain a sufficient accumulation of gas from the extinguished wick to aid in ignition. To the outer face of the upper end of said lever 4 the sparking device 15 is fixed, consisting of a spring-arm 10, having a contact-point 11 pivoted on its upper free end. This spring-arm 10 is fixed and insulated from the said lever 4 by the holding-screws 12 and 13, which pass through suitable openings in an interposed insulation-plate 14 and then through a longitudinal slot 4' in said lever 4 and out of contact therewith, the screw 12 then passing through a screw-threaded opening in a second insulating-plate 25 14' upon the inner face of the lever 4. By loosing the screw 12 the spring-arm 10 can readily be adjusted to compensate for wear upon the said pivoted contact 11. This spring-arm 10 has its upper end bent to approximately a right angle with its lower portion and so arranged as to normally project diametrically over and in close proximity to the burner, Fig. 2. The said pivoted contact 11 resembles in form a bell-crank lever, with its lower pendent arm adapted to firmly contact the said wired edge of the said burner or tube 30 when the handle 5 of the lever 4 is pressed toward the receptacle 1, the upper horizontal arm of the contact 11 bearing upon the adjacent face of said spring-arm, Fig. 2. When the lever 4 has carried the sparking-contact to the limit of its outward movement, Fig. 1, it will be out of the path of the blaze 47. On a fixed transverse pin 18 is mounted a coil-spring 35 19, to the upright end of which is secured the ends of the spring-wire loop 17, the looped end thereof passing through a proper lateral aperture in the upper end of the lever 4, immediately at the rear of the extinguishing-cap, thereby normally securing the said lever 4 and its surmounted sparking device in the 40 position shown in Fig. 2. In the opposite of said shell 6, and preferably to the upper side thereof, is fixed an insulating block or strip 23, to the lower face of which is secured, by holding-screws or in any other proper manner, one end of the metallic plate 22, whose inner free end is at all times in contact and electrical connection with the said spring-arm 10, as shown. 45 The insulated wire 24, Fig. 2, in the tubular supporting-frame has its lower end soldered to the fixed end of said plate 22, as shown.

The parallel upright sections 26 of this frame are rigidly connected at their upper end by a hollow cross piece or section 28, to which they are united by a screw-threaded connection. An integral hollow open-topped lug or casting 29, preferably cylindrical in form, is arranged midway the ends of said section 28, the bottom of which is inclined to the conical form and contains a snugly-fitted circular insulated plate 32, Fig. 4, having a central opening in which is tightly fitted a copper rivet 33, having an annular flange 44 thereon to aid in preventing displacement thereof. This rivet or post 33 has an opening or slot in its top to receive the adjacent tapered end of the metallic post 36. The upper end of the said wire 24 is soldered to the top of said rivet. The upper portion of this casting 29 is internally screw-threaded and contains a circular metallic plate 34, mounted therein by a screw-threaded connection. This plate 34 has a circular opening 45 of proper size to contain the annular lug 46 on the said post 36 without contact with said plate 34. On the upper face of the plate 34 is arranged an insulating-plate 35, secured thereto by proper holding-screws and having a central opening for the post 36, which is secured against displacement by the fixed collar 46. To the top of the post 36 the inner end of the leading-in wire 38 is soldered. The leading-out wire 39 has its inner end soldered to the said plate 34. A conical cap 30 is mounted upon said casting 29 by a screw-threaded connection. By this construction my improved lighter can readily be detached from its support at pleasure without removing or deranging the said wires 38 and 39.

The operation of my invention thus described is obvious and, briefly stated, is as follows: As the wire 38 is electrically connected to the pivoted sparking device 11 through the post 36, wire 24, plate 22, and spring-arm 10, all of which are insulated as described, and as the wire 39 is electrically connected to the wick-tube and burner through the plate 34 and the said supporting-frame, it follows that when the operator presses the handle 5 of the lever 4 from its normal position shown in Fig. 2 to the position shown in Fig. 1 against the tension of said coil-spring 17 an igniting-spark will be thrown by the momentary striking contact of the sparking device 11 with the wire 40 on the adjacent edge of the burner, as described. By this movement the extinguishing-cap and sparking device are withdrawn from the path of the blaze, Fig. 1, and by the same movement the swiveled case or shell body 6 is withdrawn from its vertical alinement with the said chambered casting 29 during the time the wick is ignited, thereby avoiding the usual smoking and tarnishing of the said casting and frame, Fig. 3. When the operator has lighted his cigar at the blaze 47, which issues an inch and one-half or two inches above the flanged opening of said shell, Fig. 3, he releases his hold upon the lever 4, allowing it under the tension of the spring 17

to resume its normal position, thereby extinguishing the blaze and storing up a limited quantity of gas in the extinguishing-cap to aid the ignition-spark in lighting the wick.

5 The oil-receptacle when released promptly resumes its vertical position by gravity. Obviously the blaze thus produced within the case or shell 6 is fully protected against the effect of sudden drafts of air usual in locations where cigar-lighters are used.

10 It is also obvious that the mere form and contour of the oil-receptacle, the shell-body, or the supporting-frame is wholly immaterial, and the means for normally securing the lever in its position may be varied at pleasure without departing from the spirit and scope of my invention, which consists, broadly, in a swiveled horizontal shell-body in which the igniting-spark is thrown by a hand-lever.

15 Having thus described my invention, what I desire to secure by Letters Patent is—

20 1. An electric cigar-lighter consisting of a horizontally-arranged containing case or shell pivotally mounted in or from a proper support, and provided with a suitable opening in its upper face for the purpose specified; a pendent wick-tube and oil-reservoir fixed in said shell; a hand-lever pivotally fulcrumed on said reservoir carrying an extinguishing-25 cap upon its inner end in co-operative relation with the burner of said wick-tube, and provided with a pivoted sparking device adapted to throw the ignition-spark within said shell; and means for normally securing 30 said lever in position.

25 2. In an electric cigar-lighter a horizontally-arranged shell or casing having a blaze-opening in the upper face thereof, and provided with a fixed wick-tube and oil-supply; 35 and means for throwing the ignition-spark within the said shell.

30 3. In an electric cigar-lighter a pivoted horizontal shell or casing having a vertical blaze-opening; a fixed wick-tube; a hand-lever pivoted on said tube and carrying an extinguishing-cap and a sparking device adapted 40 to be actuated by said hand-lever, and adapted to throw the ignition-spark within the said shell.

35 4. The combination in an electric cigar-

lighter of a vertical supporting-frame; a horizontal shell or casing 6 pivoted in from the lower portion of said frame; a pendent wick-tube fixed in or to said casing; a hand-lever fulcrumed on said tube with its inner and upper end provided with an extinguishing-cap; an insulated sparking device pivoted on said lever and adapted to throw the igniting-spark within the containing-shell by contacting the adjacent end of the wick-tube; and means 55 for automatically securing the said lever and said sparking device in their normal position after each operation.

40 5. An electric cigar-lighter comprising a horizontal shell having a vertical flame-opening, and a fixed wick-tube projecting into the same, the said shell being pivotally mounted in a proper support; and means for throwing the ignition-spark within said shell by a positive movement of an operating hand-lever 70 and a hand-lever pivoted on said wick-tube and provided with an extinguishing-cap.

45 6. In an electric cigar-lighter, means for detaching the same from its support, consisting of a hollow fixed or integral casting on 75 said frame, having on its lower portion an insulated horizontal plate, and having the periphery of its open top internally screw-threaded; a metallic post mounted in said plate for the purpose shown; a circular metallic plate mounted in the upper portion of said casting by a screw-threaded connection as shown, having a central opening for the purpose specified and having the inner end of the return-wire secured thereto; a vertical 80 insulated metallic post suspended in said opening, adapted to register and form an electrical connection with the post in said insulated plate, and having the leading-in wire connected thereto; and a detachable 85 cap adapted to close the top of said casting by a screw-threaded connection.

50 Signed by me, at Auburn, county of De Kalb, State of Indiana, this 12th day of October, A. D. 1898.

WILLIAM F. KESSLER.
